UNITED STATES PATENT OFFICE.

PAUL J. PALINKAS, OF SOUTH NORWALK, CONNECTICUT.

JIMMYPFOOF LOCK.

Application filed December 14, 1926. Serial No. 154,679.

This invention relates to locks, and particularly to a so-called jimmy proof lock in which the lock bolt is so engaged with the strike or keeper that the bolt cannot be pried away from the keeper by inserting a jimmying tool between the door and the jamb to pry them apart, and has for an object to provide an improved structure for this type of lock which will be of more simple construction than those now generally employed and so may be manufactured and assembled at less cost and will not be likely to get out of order in operation, and also to provide a structure in which the operation will be positive and reliable.

With the foregoing and other objects in view, I have devised the construction illustrated in the accompanying drawing forming a part of this specification. In this drawing,

Fig. 1 is a side elevation of a lock with the cover removed showing its relation to the keeper, and also showing the bolt in the unlocked or retracted position.

Fig. 2 is a transverse section substantially on line 2—2 of Fig. 1, and

Fig. 3 is a view similar to Fig. 1 but showing the bolt in the locked position.

The lock includes the usual casing 5 adapted to be mortised into the door and carrying the lock mechanism. This mechanism includes the movable locking bolt which is composed of three sections, an intermediate section 6 and two outer sections 7 and 8. These latter sections are the same in construction but are reversed. Each comprises a body portion and at its outer end have a laterally outwardly extending lug 9 forming a hook portion. The body portions are provided with two L-shaped slots the longer portion 10 of which extends longitudinally of the members and the shorter portion 11 extends at right angles thereto, and these slots receive guide pins 12 carried by the casing 5.

The intermediate section 6 is mounted to slide longitudinally of the casing and has a longitudinal slot 13 to receive guide pins 14 carried by the casing. It will be noted from an inspection of Figs. 1 and 3 that when the bolt is retracted the forward hook portions of the outer sections 7 and 8 are together while the body portions are separated and a portion of the intermediate section 6 is between them. The remaining portion of

the intermediate section is of greater width forming inclined or curved cam surfaces 15, and the smaller or outer end of this intermediate section is provided with similarly inclined cam surfaces 16. While in the retracted position the cams 15 engage the round corners 17 on the outer sections and the cams 16 rest against similar corners 18 on these sections. The inner section is provided with spaced shoulders 19 and 20 for coaction with the finger or follower 21 by which the bolt may be operated to and from the locking position. This finger or follower may be operated by any key controlled means, such as the well known pin tumbler cylinder, not shown. Suitable springs 22 are mounted in the casing 23 and rest adjacent their free ends 24 against the outer side edges of the outer sections 7 and 8 and tend to move these sections laterally toward each other.

Each section 7 and 8 carries a pin 25 which are adapted under certain conditions presently to be described to be engaged by a cross bar 26 carried on the intermediate member 6. This bar may be cast as an integral part of the section or it may be a separate element secured to the section by any suitable means, such as screws 27. The forward end of the bolt is adapted to pass through an opening in the plate 28 secured to the edge of the door and coacts with a keeper 29 which is preferably in the form of a plate secured to the jamb 30. This keeper has an opening 31 of sufficient size for passage of the outer ends of the two sections 7 and 8 when they are together, as indicated in dotted lines, Fig. 1, but is smaller than the distance between the outer ends when these sections are separated, as shown in Fig. 3. The open side of the casing after the lock is assembled is closed by the usual cover plate 32 secured by screws threaded into the casing at the tapped holes 33.

The operation is as follows: The normal unlocked position of the elements is shown in Fig. 1, and it will be noted that in this position the hooked outer end portions of the outer sections 7 and 8 are withdrawn from the keeper 29, and therefore, the door is unlocked. Also in this position the guide pins 12 are in the longitudinal portions 10 of the L-shaped slots in these sections, and the cams 15 and 16 engage the corners 17 and 18 respectively. If now it is desired to

lock the door the finger or follower 21 is swung to the left or counterclockwise, as viewed in Fig. 1. During the first part of its movement, or up to the dotted line position of Fig. 1, the cams 15 and 16 cooperating with the corners 17 and 18 cause the three sections 6, 7 and 8 to move forwardly as a unit because the sections 7 and 8 are held against lateral movement as the pins 12 are in the longitudinally extending portions 10 of the L-shaped slots. Therefore, the three sections move forwardly as a unit and the hook shaped outer ends 9 are passed through the opening 31 in the keeper to the dotted line position shown in Fig. 1. In this position the pins 12 engage the inner ends of the slots 10 and prevent further forward movement of the sections 7 and 8, but the pins are now in alignment with the transverse portions 11 of these slots, and therefore, the sections 7 and 8 are free to move laterally outward. Therefore, continued forward movement of the intermediate section 6 under the action of the follower 21 will cause the cams 15 and 16 to react on the corners 17 and 18 and separate the sections 7 and 8 as indicated in Fig. 3, and after they are separated they will be held in this position by engagement of the inner edges of the sections 7 and 8 with the outer edges of the intermediate section 6 as clearly shown in Fig. 3. At the completion of this action the hooks or lugs 9 are projected behind the keeper and the pins 12 are at the inner ends of the slots 11. It will be apparent that now if a jimmy were inserted between the edge of the door and the jamb and an effort made to pry them apart the lugs 9 would engage the back of the keeper 29 and prevent their separating. This will prevent the withdrawing of the bolt from the keeper by this jimmying action. It will also be apparent that as now the pins 12 are within the transverse slots 11 the bolt sections cannot be pushed back into the door by means of a tool pressed against the free ends thereof.

In unlocking the door these movements are reversed and swinging of the follower or finger 21 to the right or clockwise as viewed in Fig. 3, will first move the intermediate section 6 inwardly or to the right. The outer sections 7 and 8 will be held stationary by the pins 12 until the section 6 has been retracted sufficiently to allow the corners 17 and 18 to run down the cams 15 and 16. At this time the sections 7 and 8 will be moved inwardly toward each other by the springs 22 until the pins 12 are in alignment with the portions 10 of the L-shaped slots. At about this time the cross bar 26 carried by the intermediate section 6 engages the pins 25 carried by the outer sections 7 and 8 and through them further backward movement of section 6 will carry sections 7 and 8 with

it to the original position shown in full lines Fig. 1, and thus the bolt is completely removed from the keeper.

It will be apparent from the foregoing that the lock is very simple in construction, that the action is positive in both directions, that during the first part of the locking movement, or the movement to pass the projecting or outer ends of the bolt into the keeper, the three sections of the bolt move as a unit and then the longitudinal movement of the outer sections is arrested and they are separated to cause their hooked portions to engage in back of the keeper by further longitudinal movement of the intermediate section. On the reverse or unlocking movement the first part of the movement of the intermediate section allows the outer section to be moved inwardly to bring the hooked end portions from alignment with the rear wall of the keeper, and then the three sections move as a unit to withdraw the bolt from the keeper. This construction effectively prevents separation of the bolt and the keeper by a jimmying action, and the projecting bolt sections are locked, so that they cannot be forced inwardly by a tool, because of the holding action of the pins 12.

Having thus set forth the nature of my invention, what I claim is:

1. In a lock, a bolt comprising three sections movable together as a unit from retracted to extended position, means mounting the outer sections for sliding movements both longitudinally and laterally and said sections having outwardly extending hook portions at their outer ends, coacting means on the central and other sections to slide the outer sections laterally on further continued movement of the central section, and means for operating the central section.

2. In a lock, a bolt including a locking section and an operating section, a casing, said locking section being provided with a pair of substantially L-shaped slots, guide pins on the casing extending into said slots, means for guiding the operating section for reciprocatory movements, cooperating cam surfaces on the two sections causing them to first move as a unit to project the locking section and then to cause the locking section to move laterally upon further movement of the operating section, and means for reciprocating the operating section.

3. In a lock, a bolt comprising a pair of locking sections and an operating section, means for guiding the operating section for reciprocatory movements, said locking sections each having a hook shaped end, the hooks extending outwardly in opposite directions, said locking sections being each also provided with a pair of substantially L-shaped slots, stationary guide pins in said slots adapted to arrest longitudinal movement of the sections at a given point, the op-

erating section extending between the other sections and provided with cam surfaces engaging surfaces on the other sections to cause the sections to move forwardly as a

5 unit to extend the hooks and when the locking sections are arrested by the guide pins to separate said sections, and means for shifting the operating section.

4. In a lock, a bolt comprising a pair of locking sections and an operating section, a longitudinal slot in said operating section, guide pins in said slot, said locking sections each having a hook shaped end, the hooks extending outwardly in opposite directions, 10 said locking sections being each provided with a pair of substantially L-shaped slots arranged with the body portions thereof extending longitudinally of the sections and the cross portions extending transversely of 15 the sections and toward the opposite section, a casing, guide pins carried by the casing and extending into said slots, the operating section extending between the locking sections, means for reciprocating the operating 20 section, coacting cam surfaces on the sections to cause them to move forwardly as a unit to project the hooks from the casing while the guide pins are in the body portion of 25 the slots and to move the locking sections laterally outward with the pins in the transverse portions of the slots.

5. In a lock, a bolt including a locking section and an operating section, said locking section having a laterally extending hook portion at its outer end, means for guiding said locking section for longitudinal movement without lateral movement and for lateral movement without longitudinal movement, means for guiding the operating 30 section for longitudinal movement, cooperating means carried by the sections to cause them to first move longitudinally as a unit

to extend said hook portion and then to shift the locking section laterally, a lost motion connection between the sections to withdraw 45 the locking section, and means for shifting the operating section.

6. In a lock, a bolt including a locking section and an operating section, said locking section having a laterally extending hook portion at its outer end and a pair of substantially L-shaped slots arranged with the cross bar thereof extending transversely of the section, guide pins in said slots, means for guiding the operating section for longitudinal movement, cooperating cam means on the sections to cause them to first move outwardly as a unit and then to shift the locking section laterally, means for shifting the operating section, and a lost motion connection between the sections to retract the locking section.

7. In a lock, a bolt comprising a pair of locking sections and an operating section, said locking sections being each provided with a hook portion at its outer end and arranged with the hook extending laterally outward, means for guiding the locking sections for movement first longitudinally forward and then laterally outward in opposite directions, means for guiding the operating section for longitudinal movement, coacting cam means on the sections to cause them to first move longitudinally as a unit and then to shift the locking sections laterally outward on further movement of the operating section, means to shift the operating section, a lost motion connection between the operating and the locking sections to retract the latter, and springs tending to shift 70 the locking sections laterally inward.

In testimony whereof I affix my signature this 22nd day of November, 1926.

PAUL J. PALINKAS.
